AIR BLAST BREAKER INTERRUPTING HEAD
WITH INTERRUPTED LINE CONTACTJoseph M. Ramrath, Mattapan, Mass., assignor to
Allis-Chalmers Manufacturing Company, Milwaukee, Wis.

Application December 19, 1951, Serial No. 262,417

7 Claims. (Cl. 200—148)

1

This invention relates in general to improvements in electric circuit breakers, and more particularly to means for improving the interrupting ability of circuit breakers of the fluid blast type.

Circuit breakers of the fluid blast type, especially those of the air blast type, are used to interrupt relatively large currents in a short period of time. This type of circuit breaker is usually provided with arcing contacts for opening the power circuit and main contacts for carrying the current when the circuit breaker is closed.

As the currents to be interrupted by circuit breakers of the fluid blast type become increasingly greater, it becomes desirable to operate the breaker in shorter periods of time and to utilize the fluid blast at a higher degree of efficiency so that the blast might extinguish the arc within the shortest possible time.

To extinguish the arc rapidly the power current must be transferred from the main contacts to the arcing contacts with a minimum of arcing. It is imperative, therefore, to have the main contact separating line exposed to an air blast which will quickly extinguish any arcing which might occur between the main contacts.

In accordance with this invention a fluid blast circuit interrupter is provided which employs a pair of separable nozzle and plug type arcing contacts and a pair of separable annular main contacts which engage along contact surfaces of the circular contact line type. At least one of the main contacts is convex immediately adjacent the circular contact line. A plurality of grooves are arranged in at least one of the main contacts and intersect the line type contact surface thereof substantially at right angles for subdividing the line type contact surface into a plurality of spaced sectors. The grooves and the gap formed between the line type contact surface upon separation of the main contacts are substantially the only avenue for admitting fluid under pressure to the arcing nozzle contact forming part of the arcing contact structure.

It is, therefore, one object of the present invention to provide a new and improved circuit interrupting structure of the fluid blast type in which arcing at the main contacts is suppressed.

Another object of this invention is to provide a new and improved fluid blast arc extinguishing structure in which the fluid blast envelops laterally the arc formed between the arcing contacts and in addition thereto tends to separate the arcing contacts.

A further object of this invention is to provide a new and improved main contact structure in

2

which the configuration of the contact structure aids arc extinguishment.

Objects and advantages other than those set forth will be apparent from the following description when read in connection with the accompanying drawings, in which:

Fig. 1 is a view in axial cross section, of an interrupting chamber of a gas blast circuit breaker involving the present invention;

Fig. 2 is a plan view of the stationary main and arcing contact structures; and

Fig. 3 is a vertical section through the contact structure taken along the line III—III of Fig. 2.

Referring more particularly to the drawing by characters of reference, Fig. 1 illustrates an interrupting head 1 comprising a flange or supporting base member 2 which is clamped by means of cap screws 3 on a cap 21 connecting the flange to a source of arc extinguishing fluid under pressure. Base member 2 supports a tubular insulator 4 of ceramic or other suitable insulating material of which porcelain is an example. A force is applied to a continuous clamping ring 5 by a series of screws 6 secured to base member 2 and a component of this force is transmitted through a split ring 7 onto the porcelain insulator 4 in a direction substantially perpendicular to a surface 8 of porcelain insulator 4 to secure the porcelain insulator to base member 2. This clamping structure minimizes bending moments and shear stresses in the porcelain.

A conductive annular member 9 made in two parts is mounted on and supported by insulator 4 by means of a continuous clamping ring 10, a split ring 11 and screws 12 in a manner similar to that used to secure insulator 4 to base member 2. An insulating tube 13 mounted within and axially aligned with insulator 4 is rigidly supported by a depending portion 14 of the annular member 9 and screwed thereto by a coupling 15. Insulating tube 13 also surrounds a pair of cooperating arcing contacts 16 and 17 of the nozzle and plug type and cooperates with conductive cylindrical member 9 to define an arcing or contact chamber 18.

The so-called fixed arcing contact 17 is mounted on a piston 19 for limited movement therewith. Piston 19 is arranged within a cylinder 20 which, in turn, is threaded into a hollow cylindrical main stationary contact forming a sleeve 22.

The main stationary contact 22 is secured to the base member 2 by bolts 23 inserted in the screw holes 24 shown in Figs. 2 and 3. Contact 22 may be considered as a part of a flow distri-

bution member 33 and defines with insulator 13 an annular chamber therebetween. Notches or grooves 25 are provided at the entrance of the screw holes 24. One purpose of grooves 25 is to provide the necessary clearance for the heads of bolts 23 and for a wrench serving to insert the bolts into the structure and to remove them therefrom. Another purpose of grooves 25 is to provide a passageway for the fluid under pressure through the main contact structure to the arcing contacts.

The arcing contact 17 and piston assembly 19 are resiliently urged into engagement with the cooperating arcing contact 16 by a beryllium copper spring 26. The spring 26 has a dual purpose, namely, to provide contact pressure between the arcing contacts 16 and 17 until the piston has been stopped in its upward movement by an abutment 51 on cylinder 20 and to act as a current carrier during the circuit interrupting operation.

The cooperating movable arcing contact 16 comprises an annular shaped arcing portion defining an orifice 27 and adapted to partially surround the top portion of fixed arcing contact 17 upon engagement therewith. Contact 16 is mounted on the sleeve shaped movable main contact 28 and forms therewith the piston 32 of a fluid motor. Sleeve 28 is adapted to slide within guiding surfaces including downward extension portion 29 of the conductive cylindrical member 9 and a bushing mounted within insulator 13. The upward stroke of sleeve 28 is limited by abutment of an annular projection 30 thereof against a flange 31 backed by suitable shock absorbing material. The interior of sleeve 28 is insulated by a suitable material and forms with hollow insulator 13 the arcing chamber 18.

The arcing chamber 18 extends upward to a suitable outlet 34 extending between member 9 and a concave baffle or cover 35 secured thereto. Arcing chamber 18 contains an auxiliary arcing electrode 36. This electrode, which is secured to cover 35 and in electrical contact with member 9, is usually axially aligned with sleeve 28.

A plurality of rigid interconnecting conductors 37 electrically connect the movable contacts 16 and 28 to member 9, which is provided with a terminal lug 38 and therefore constitutes a stationary terminal element. Base member 2, which is electrically connected to the stationary contact 22 constitutes the second stationary terminal element and is provided with a suitable terminal lug (not shown).

Each rigid interconnecting conductor 37 is in the form of a rocking contact lever which is in permanent contact with the conductive cylindrical member 9 and sleeve 28 at all times. Sleeve 28 may be provided with a groove 39 having a concave cross section extending around the circumference thereof and forms a bearing surface for engagement of one end of the interconnecting conductors 37. The conductor annular member 9, in turn, may be provided with a concave circular groove 40 having an annular supporting surface adapted to hingedly support the other end of conductors 37. Levers 37 extend in radial directions from sleeve 28 and, while resting on their supporting surfaces, make with the axis of sleeve 28 an angle which varies with the longitudinal position of the sleeve. A plurality of dual purpose spring means 41 axially aligned with a plurality of pins 42, provide a substantially constant pressure between flanges 31 and interconnecting conductors 37.

Thus, as piston 32 moves under the influence of air pressure, sleeve 28 moves upward in the interrupting head 1 and interconnecting conductors 37 follow the vertical movement thereof by a combined rolling and wiping action over the two contact surfaces associated therewith. Pairs of ears 43 provided on member 9 guide each interconnecting conductor 37 and align these interconnecting conductors in radially extending directions from the annular groove 39 on the outer surface of sleeve 28. Interconnecting conductors 37 may be shaped in any one of a number of ways, however, the chosen configuration must permit a freedom of movement over the supporting surfaces engaging therewith. The operable interconnecting conductors illustrated in the drawing are provided with convex end portions in engagement with the supporting surfaces, whereby movement of interconnecting conductors 37 takes place with a minimum of friction.

The helical spring means 41 act upon interconnecting conductors or levers 37 at points intermediate their ends to provide a sufficient amount of contact pressure between conductors 37 and the contact surfaces engaged therewith. However, these springs have a dual function and additionally effect resetting or reclosing of contact 16 upon the decrease of pressure in the arcing chamber 18 upstream of movable contact 16. The helical spring means 41 are disposed so as not to increase the overall dimensions of the circuit breaker. The stroke or compression of spring means 41 upon movement of the movable contact 16 is smaller than the stroke of contact 16.

Base member 2 provides a connection between a reservoir (not shown) constituting a source of arc extinguishing fluid under pressure and an inlet portion 44 of the arcing chamber 18 for directing a blast of arc extinguishing fluid under pressure between the arcing contacts and through the arcing chamber. The arc extinguishing fluid under pressure may be an inert gas such as nitrogen, but it will be assumed herein that the fluid is air under pressure of the order of two hundred or more pounds per square inch supplied to the reservoir by a suitable compressor (not shown).

Inlet port 44 is connected to a plurality of passageways 45 which conduct the fluid under pressure from port 44 around the main stationary contact 22 to the outside periphery of the main contact structure.

As shown more clearly in Fig. 2, the contact surface 46 of the main stationary contact 22 is a flat surface divided into a plurality of segments by the notches 25. The sleeve 28 is provided with a convex main contact surface 47 which provides upon contact with the cooperating flat contact surface 46 a circular line type contact. The notches 25 provided in the flat contact surface 46, however, divides the circular line contact into four circular line contact segments. A passageway 50 is provided through the stationary contact 22 to the under side of piston 19. Part of the fluid under pressure passing through inlet port 44 will traverse passageway 50 to assist spring 26 in urging contact 17 in engagement with contact 16.

In operation, the circuit breaker being closed as indicated in Fig. 1, current flows through a stationary terminal element (not shown), base member 2, main stationary contact 22, flat contact surface 46, convex contact surface 47, sleeve 28 of piston 32, conductors 37, conductive an-

nular member 9, and stationary terminal element 38. Opening of the circuit breaker is initiated by applying a blast of air under pressure through base member 2 and through the passageways 45 formed between insulating tube 13 and contact 22. Fluid under pressure passes through notches 25 to the annular surface of movable contact 16 against the action of the dual purpose springs 41. Upon separation of the main contact surfaces 46 and 47 the current path is shifted and passes from the base member 2 to the main stationary contact 22, beryllium copper spring 26, piston 19, arcing contact 17, arcing contact 16, sleeve 28 of piston 32, conductor 37, conductive annular member 9, and stationary terminal element 38.

The shape of the stationary contact casting 22 permits maximum air flow over the main contacts at their time of separation. If the current transfer from main to arcing contacts is not perfect, possible arcing may occur at the main contact separating line. It is imperative, therefore, to have the main contact separating line under as good an air flow as possible. The rounded bottom of the movable main contact surface 47 provides a line contact on the top of the main stationary contact surface 46, thus permitting the fluid blast from passageways 45 to be present at the separation of the main contact surfaces 46 and 47 and at the inception of any main contact arcing.

The arcing contact 17 is mounted on piston 19 which in turn is located on the inside of the stationary contact casting 22. The arcing contact assembly 17 is carried by the beryllium copper spring 26. This spring 26 has a dual purpose, namely to provide contact pressure until the piston is stopped in its upward movement by abutment 51 on its cylinder 20, and to act as a current carrier. Spring 26 carries the total current after the main contacts separate and until the abutment 51 on cylinder 20 has been reached by piston 19, and from then on the spring 26 carries the arc current until arc extinction. One reason for mounting the arcing contact on a piston assembly is to use that assembly as an additional pressure area to provide upward movement for the movable main contact sleeve 28.

Initially, during the circuit breaker opening operation, there will be air leakage on the outside of the stationary main contact through passageways 45 through the notches 25, into the cylinder 20, and around the arcing contact piston 19. Further leakage of air occurs from passageway 50 and around the piston 19. This leakage of air around piston 19 ceases when piston 19 reaches the abutment on cylinder 20. At this point the entire air supply is directed over the main line type contact into the hollow arcing contact piston 32. Lateral clearance around piston 19 provides self-adjustment of the arcing contacts 16, 17.

Accordingly, a new and improved circuit breaker structure has been disclosed comprising a pair of cooperating arcing contacts connected in parallel with a pair of cooperating main contacts. The main contacts provide a convex surface on one main contact to form a line contact with the flat surface of the other main contact. A plurality of grooves are arranged on the flat surface of the one main contact for intersecting the line contact substantially at right angles for subdividing the line contact into a plurality of spaced line or arcuate segments. Means are provided for conducting a flow of fluid under

pressure from a source through the grooves and the gaps formed between the main contacts upon separation thereof and over the cooperating surfaces of the arcing contacts to atmosphere. The fluid path is substantially the only avenue from the source for admitting fluid under pressure to the arcing contacts.

Although but one embodiment of the present invention has been illustrated and described, it will be apparent to those skilled in the art that various changes and modifications may be made therein without departing from the spirit of the invention or from the scope of the appended claims.

It is claimed and desired to secure by Letters Patent:

1. In a fluid blast circuit interrupter, a source of fluid under pressure, a contact chamber, a pair of main contacts mounted within said chamber and comprising a movable sleeve providing a convex contact surface cooperating with a stationary sleeve providing a flat contact surface, said movable and stationary sleeves engaging to form a line contact, a pair of cooperating arcing contacts connected in parallel with said main contacts and adapted to draw an arc in said chamber, said arcing contacts comprising a movable arcing contact arranged in said movable sleeve and defining an orifice and a fixed arcing contact arranged in said stationary sleeve for limited movement therein, means for separating said main and arcing contacts, spring biasing means for maintaining said arcing contacts closed until said movable sleeve has moved a predetermined distance, and means defining a path for the flow of fluid from said source over first the cooperating surfaces of said main contacts, second the cooperating surfaces of said arcing contacts and third through said orifice defining movable arcing contact to atmosphere.

2. In a fluid blast circuit interrupter, a source of fluid under pressure, a supporting base member, means defining a blast passage adapted to be supplied with fluid under pressure from said source, a flow distribution member arranged coaxially within said passage in spaced relation from the boundary walls thereof to define an annular chamber therebetween, a pair of separable annular main contacts engaging along a pair of contact surfaces of the circular contact line type, at least one of said surfaces being convex immediately adjacent said circular contact line, one of said main contacts being arranged at the down-stream end of said flow distribution member and the other of said main contacts being spring biased to contact closed position and having a pressure reactive surface immediately adjacent said pair of line type contact surfaces for causing separation of said main contacts under the action of fluid under pressure supplied from said source, a pair of separable nozzle and plug type arcing contacts each supported by one of said main contacts, said flow distribution member having a plurality of longitudinal angularly spaced grooves intersecting one of said line type contact surfaces and subdividing said one of said line type contact surfaces into a plurality of spaced segments, said flow distribution member being provided with holes coaxially aligned with said longitudinal angularly spaced grooves, and bolts inserted in said coaxially aligned grooves and holes and threaded into said base member for securing said distribution member to said base member.

3. In a fluid blast circuit interrupter, a source

of fluid under pressure, a contact chamber, a pair of main contacts mounted within said chamber and comprising a movable sleeve providing a convex contact surface cooperating with a stationary sleeve providing a flat contact surface, said movable and stationary sleeves engaging to form a line contact, a plurality of grooves in one of said main contacts intersecting said line contact substantially at right angles for subdividing said line contact into a plurality of spaced segments, a pair of cooperating arcing contacts connected in parallel with said main contacts and adapted to draw an arc in said chamber, said arcing contacts comprising a movable arcing contact arranged in said movable sleeve and defining an orifice and a fixed arcing contact arranged in said stationary sleeve, means for sequentially separating said main contacts and said arcing contacts, and means defining a path for the flow of fluid from said source through said grooves, over the cooperating surfaces of said main contacts, over the cooperating surfaces of said arcing contacts and through said orifice to atmosphere.

4. In a fluid blast circuit interrupter, a source of fluid under pressure, a contact chamber, a pair of main contacts mounted within said chamber and comprising a movable sleeve providing a convex contact surface cooperating with a stationary sleeve providing a flat contact surface, said movable and stationary sleeves engaging to form a line contact, a plurality of grooves in one of said main contacts intersecting said line contact substantially at right angles for subdividing said line contact into a plurality of spaced segments, a pair of cooperating arcing contacts connected in parallel with said main contacts and adapted to draw an arc in said chamber, said arcing contacts comprising a movable arcing contact arranged in said movable sleeve and defining an orifice and a spring biased fixed arcing contact arranged in said stationary sleeve for limited movement therein, means for sequentially separating said main contacts and said arcing contacts, and means defining a path for the flow of fluid from said source through said grooves, over the cooperating surfaces of said main contacts, over the cooperating surfaces of said arcing contacts and through said orifice to atmosphere.

5. In a fluid blast circuit interrupter, a source of fluid under pressure, a contact chamber, a pair of main contacts mounted within said chamber and comprising a movable sleeve providing a convex contact surface cooperating with a stationary sleeve providing a flat contact surface, said movable and stationary sleeves engaging to form a line contact, a plurality of grooves in one of said main contacts intersecting said line contact for subdividing said line contact into a plurality of spaced segments, a pair of cooperating arcing contacts connected in parallel with said main contacts and adapted to draw an arc in said chamber, said arcing contacts comprising a movable arcing contact arranged in said movable sleeve and a fixed arcing contact arranged in said stationary sleeve, means for sequentially separating said main contacts and said arcing contacts, and means defining a path for the flow of fluid from said source through said grooves, over the cooperating surfaces of said main contacts, over the cooperating surfaces of said arcing contacts to atmosphere.

6. In a fluid blast circuit interrupter, a source of fluid under pressure, means defining a blast passage adapted to be supplied with fluid under pressure from said source, a flow distribution

member arranged coaxially within said passage in spaced relation from the boundary walls thereof to define an annular chamber therebetween, a pair of main contacts mounted within said passage and comprising a movable sleeve providing a convex contact surface cooperating with a stationary flat contact surface arranged at the downstream end of said flow distribution member, said main contacts engaging to form a line contact, said movable sleeve being spring biased to contact closed position and having a pressure reactive surface immediately adjacent said line contact for causing separation of said main contacts under the action of fluid under pressure supplied from said source, a pair of cooperating arcing contacts connected in parallel with said main contacts and adapted to draw an arc in said passage, said arcing contacts comprising a movable arcing contact arranged in said movable sleeve and defining an orifice and a fixed arcing contact arranged in said flow distribution member for limited movement therein, spring biasing means for maintaining said arcing contact closed until said movable sleeve has moved a predetermined distance, said flow distribution member having a plurality of longitudinal angularly spaced grooves intersecting said flat contact surface and subdividing said line contact into a plurality of spaced segments for admitting a plurality of angularly spaced flows of fluid under pressure from said annular chamber to said pressure reactive surface.

7. In a fluid blast circuit interrupter, a source of fluid under pressure, means defining a blast passage adapted to be supplied with fluid under pressure from said source, a flow distribution member arranged coaxially within said passage in spaced relation from the boundary walls thereof to define an annular chamber therebetween, a pair of main contacts mounted within said passage and comprising a movable sleeve providing a convex contact surface cooperating with a stationary flat contact surface arranged at the downstream end of said flow distribution member, said main contacts engaging to form a line contact, a pair of cooperating arcing contacts connected in parallel with said main contacts and adapted to draw an arc in said passage, said arcing contacts comprising a movable arcing contact arranged in said movable sleeve and a fixed arcing contact arranged in said flow distribution member for limited movement therein, spring biasing means for maintaining said arcing contacts closed until said movable sleeve has moved a predetermined distance, means for separating said main and arcing contacts, said flow distribution member having a plurality of longitudinally angularly spaced grooves intersecting said flat contact surface and subdividing said line contact into a plurality of spaced segments for admitting a plurality of angularly spaced flows of fluid under pressure from said annular chamber through said grooves and over the cooperating surfaces of said arcing contacts to atmosphere.
